MEANS FOR WELL DRILLING

Odie Colquitt, Denver, Colo., assignor to The Winter-
Weiss Company, Denver, Colo.

Application March 7, 1956, Serial No. 569,987

3 Claims. (Cl. 255—24)

This invention relates to well drilling, and more particularly to the type of well drilling used for relatively large diameter water wells and known as "reverse flow" drilling, such as described in applicant's prior Patent No. 2,657,015.

In reverse flow drilling the well is maintained filled with water which flows into the well at the ground surface and is drawn from the well together with the drill cuttings, mud, rocks, etc. through the drill pipe. Such a method has been found highly satisfactory in drilling comparatively shallow wells. For deeper wells, however, it has been difficult to lift the mud, rocks, debris and water through the drill pipe due to internal friction in the long drilling string of pipe.

The principal object of this invention is to provide means for drilling relatively deep wells by the reverse flow method in which the ascending mud, water and debris will be aerated as it approaches the surface so as to decrease the density thereof, thereby relieving the weight of the ascending fluid column and decreasing the friction on the drill pipe so as to make deep drilling commercially practical.

Another object of the invention is to provide highly efficient means for furnishing compressed air to the rotating drill string of drill pipe at any desired depth in the well, and to so construct the air supply means that it will not interfere in any way with the normal well drilling operations.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a fragmentary side view of the upper portion of a string well drilling mechanism, illustrating the invention applied thereto;

Fig. 2 is a continuation of Fig. 1, illustrating a lower portion of the tool string partially broken away to show the interior construction;

Fig. 3 is an enlarged fragmentary vertical section, taken on the line 3—3, Fig. 1;

Figs. 4 and 5 are cross-sections, taken on the lines 4—4 and 5—5, respectively, Fig. 1; and

Figs. 6 and 7 are similar cross-sections, taken on the lines 6—6 and 7—7, respectively, Fig. 2.

This invention applies to a well drilling rig of the type in which a "Kelly," to which the string of drill pipe is attached, is suspended from a swivel supported by the draw works of the rig. The kelly is rotated by any suitable conventional rotary table mechanism and a stationary suction pipe extends through the swivel and into the kelly, the latter being vertically slidable on the suction tube.

The present invention employs a swivel housing 10 which is supported from the draw works by means of suitable hangers 11. The swivel housing is provided with oppositely projecting bracket arms 36 which engage slides 5 in the draw works to prevent rotation of the housing as described in applicant's prior Patent No. 2,657,015.

The swivel housing is provided with upper and lower annular ball races in which suitable steel thrust balls 12 travel. The thrust balls rotatably support a swivel core 13 within the swivel housing 10.

A cylindrical bearing sleeve 14 is sweated or otherwise secured about the core 13. The bearing sleeve 14 is sealed to the housing 10 above and below the ball races therein by means of suitable expansive, annular sealing gaskets 15. The core 13 is provided with any suitable wear liners 16 which are retained in place therein by means of a threaded, annular, spanner cap 17.

The core 13 is positioned about a stationary suction pipe 18 and is both vertically and rotatably movable on 20 the suction pipe 18. The suction pipe 18 is supported from a suction fitting 47 leading to the intake of a suction pump as described in applicant's said prior Patent No. 2,657,015.

The core 13 is provided with an annular, internal 25 cavity which forms an air jacket 19 therein. The air jacket 19 opens through the bottom of the core 13 through spaced-apart air ports 20. Air is supplied to the air jacket 19 through a compressed air pipe 21, which in in actual practice would be connected through the medium of a flexible hose with a suitable air compressor.

The air pipe 21 is threaded into an air intake boss 22 on the swivel housing 10 which communicates with an annular air chamber 49 surrounding the core 13. Air is continuously admitted to the air jacket 19 from the chamber 49 during the rotation of the core through air 35 passages 23. The air enters the swivel 10 between the upper and lower sets of sealing gaskets 15 so that the latter act to prevent the escape of air from between the swivel housing and the swivel core.

The "kelly" of the present invention comprises a Kelly tube 24 within which the suction pipe 18 terminates. Vertically positioned angle irons are welded in axial alignment and spacer-apart relation to the external surface of the Kelly tube 24 to form a substantially square cross-section. Two of these angle irons, which will be designated as guide angles 25, terminate in spaced relation to the upper and lower extremities of the Kelly tube 24. The remaining two angle irons, which will be herein designated as air conducting angles 26, extend the full 45 length of the Kelly tube 24 and are welded to a lower Kelly tube flange 27 and an upper Kelly tube flange 28. The air conducting angles 26 communicate through the flanges 27 and 28 through triangular air ports 29 formed therein.

50 The upper flange 28 of the Kelly tube 24 is bolted to a lower flange 30 on the swivel core 13 by means of suitable attachment bolts 31 so that the two triangular ports 29 therein will align with two of the air ports 20 of the core 13 so that air will be conducted from the air jacket 19 through the air conducting angles 26 and through the lower Kelly flange 27. As illustrated, there are two pairs of oppositely-positioned ports 20 in the core 13 so that the Kelly flange 28 with its two oppositely positioned ports 29 can be secured in either of two positions at 90° to each other.

55 The Kelly tube 24 passes through an opening in a conventional rotary drilling table and is locked against rotation relative to the table by means of slips which form a rectangular opening corresponding to the rectangular cross-section of the Kelly tube 24. The con-

struction and use of rotary tables, slips, and square Kelly bars is well known in the art.

The lower Kelly flange 27 is bolted to the upper section of a plurality of sections of drill pipe 32 by means of suitable bolts 35. Each of the sections of the plurality of sections of drill pipe comprises a length of drill pipe 32 to the extremities of which connecting flanges 33 are welded. The flanges 33, shown more in detail in Fig. 7, are formed with three openings, a large opening about which the drill pipe 32 is welded, and two diametrically opposite smaller openings about which air tubes 34 are welded.

When a string of the sections 32 are bolted together, the smaller openings in the flanges 33 thereof align with each other so that air can flow from the air jacket 19 through the air tubes 34 of the entire string.

The string of sections terminate in an air-jacketed section 37 which is bolted to the lowermost section of the string by means of suitable attachment bolts 38. The air-jacketed section 37 is provided with air tubes 39 which communicate, through ports in an upper flange 40 thereon, with the air tubes 34 of the next above section. The air tubes 39 on the jacketed section 37 are provided with check valves 41 of any suitable conventional type which act to prevent upward flow through the air tubes.

The check valves 41 discharge through nipples 42 into a cylindrical air manifold 43 sealed to and circumferentially surrounding the air-jacketed tube 37. A plurality of air jet openings 44 are formed through the jacketed section 37 within the manifold 43.

The jacketed section 37 terminates at its lower extremity in a conventional pipe flange 45 from which the usual drill pipe sections of the drilling string, indicated at 46, are suspended. The latter drill pipe sections extend to and terminate in any suitable well drilling bit of the reverse flow variety.

In use, the well is completely filled with water and the air manifold 43 is positioned in the drilling string intermediate the drill and the ground surface. Water is continuously supplied into the mouth of the well, indicated in broken line at 48 in Fig. 1. This water flows to the bottom of the well thence through the drilling bit and upwardly through the drilling string 46, the jacketed section 37, the sections 32, the Kelly tube 24, the suction pipe 18, thence to the suction pump. After the debris has been settled from the water, the latter is returned to the well, for reuse as above described as is customary in reverse flow drilling. As the well increases in depth, the swivel is lowered along the suction pipe 18.

It is desired to call attention to the fact that the weight of the ascending column of mud and water up to the ground surface is substantially balanced by the weight of the water filling the well. The only "head" which must be overcome by atmospheric pressure, when the suction pump creates a partial vacuum over the ascending column, is from the ground surface to the pump. However, there is also friction between the mud and drill pipe to contend with and as the well deepens this friction retards the upward to such an extent as to make further drilling impractical.

However, with the use of this invention, this difficulty is overcome for if the manifold 43 be positioned intermediate the surface and the drill it will be found that when the suspended mud and debris reaches the air manifold 43, it will be completely permeated with air entering under pressure through the jets 44. This permeation will instantly expand the water, mud and debris to reduce the density and increase the buoyancy

thereof so as to reduce the friction on the drill pipe and allow free flow to the surface.

Should the air pressure fail, the hydraulic pressure in the well would tend to force mud upwardly in the air pipes. This is prevented, however, by the check valves 41 which close whenever the hydraulic pressure exceeds the pneumatic pressure.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. Means for aerating a rising column of mud in a well drilling apparatus of the reverse flow type having a stationary vertical suction pipe suspended over a well comprising: an annular hollow swivel core slidably surrounding said suction pipe; an annular swivel housing surrounding said swivel core, the interior of said housing being in communication with the hollow interior of said swivel core; thrust bearings between said housing and said core, said bearings allowing rotation of said core in said housing and preventing relative axial movement therebetween; means for supporting said housing on said suction pipe; means for admitting air under pressure to said housing; a Kelly tube suspended from said core about said suction pipe for conducting mud to the interior of said suction pipe; a longitudinally extending air conduit on the exterior of said Kelly tube in communication at its upper extremity with the hollow interior of said core; a plurality of connected sections of drill pipe secured to and suspended from said Kelly tube for conducting mud into the interior of said Kelly tube; a longitudinally extending air tube mounted on the exterior of each section of drill pipe, said air tubes being in communication with each other and with the air conduit on said Kelly tube; a cylindrical air manifold surrounding one of the lowermost sections of drill pipe, said manifold being of larger diameter than said latter section; means sealing each extremity of said air manifold to said latter section to form a closed, cylindrical air chamber thereabout, the air tubes of the superimposed sections being in communication with said chamber to supply air thereto from the hollow interior of said swivel core, there being jet openings in the wall of said latter drill pipe section directing air jets from said chamber into the interior of said latter section; and a tubular drilling string attached to and suspended from said latter section for conducting mud from said well to said connected sections of drill pipe.

2. A well drilling apparatus as described in claim 1 in which the external air passage on said Kelly tube comprises an angle iron welded along its edges to said Kelly tube so that the interior of said iron will form said air passage, and so that said angle iron will form a projection on said Kelly tube through which rotation may be imparted to said Kelly tube.

3. Means for aerating a rising column of mud as described in claim 1 having a check valve positioned in the path of flow from said air tubes to said air chamber to prevent reverse flow from said chamber to said tubes.
